MAGNETICALLY OPERATED SWITCH

Adele S. Raettig, Hoboken, N. J.

Application September 2, 1942, Serial No. 456,992

1 Claim. (Cl. 200—87)

1

This invention relates to a switch and refers more particularly to a magnetically operated selective switch used for energizing or otherwise influencing any one of several circuits.

An object of the present invention is the provision of an effectively operating circuit controller or switch of simple, compact and sturdy construction, which is inexpensive to manufacture and which may be conveniently utilized for the purpose of closing any one of a comparatively large number of circuits.

Another object is the utilization of a permanent magnet for the purpose of actuating selectively any one of several levers used for establishing an electrical connection between a number of terminals.

Other objects of the present invention will become apparent in the course of the following specification.

In accomplishing the objects of the present invention it was found desirable to provide a central terminal, which may be grounded, if desired, and to arrange other terminals about the central terminal, each of said other terminals being provided with a separate magnetizable conducting swingable member which may be attracted by a permanent magnet to provide an electrical connection between the terminal carrying the member and the central terminal. The magnet may be carried by means making it possible to shift the position of the magnet in order to be able to energize or deenergize any one of the several swingable members.

The invention will appear more clearly from the following detailed description when taken in connection with the accompanying drawing showing, by way of example only, a preferred embodiment of the inventive idea.

In the drawing:

Figure 1 is a top view, with a part of the cover removed, of a switch constructed in accordance with the principles of the present invention.

Figure 2 is a section along the line 2—2 of Figure 1.

Figure 3 is a section along the line 3—3 of Figure 1.

Figure 4 is a perspective view of a swingable element.

The switch shown in the drawing is situated in a round insulating box 5 closed by an insulating disc or cover 6 which is firmly attached to the box 5 by screws 7. Partitions 8 extend radially within the box 5 and are firmly connected to its bottom 9 and side wall 10. The partitions 8 separate the interior of the box into compartments

2

11, the number of which is equal to the number of terminals 12 which are to be controlled by the switch.

Each terminal 12 has the form of a conducting bolt 13 extending through the bottom 9 of the casing and carrying a nut 14 and a wire 15 leading to any suitable circuit not shown in the drawing. The upper end of the bolt 13 has the form of a cylinder 16 having recesses which contain two opposed ends 17 of a swingable conducting plate 18 shown separately in Figure 4. Thus the plate 18 is pivotally or swingably supported by the cylinder 16. The plates 18 are made of any suitable conducting and magnetizable material.

In each compartment 11 there is a separate plate 18 carried by its terminal 12. The terminals 12 are preferably arranged along a circle in the center of which the central terminal 19 is located. The plates 18 are normally situated in a somewhat inclined position with their lower ends located below a conducting disc 20 carried by a cylinder 21 constituting a part of the central terminal 19.

The cylinder 21 is integral with a conducting bolt 22 extending through the bottom 9 and carrying a nut 23 and a wire 24.

The wire 24 may be grounded, or it may be connected to a circuit or a part of a circuit which is to be electrically connected with any one of the terminals 12.

The electrical connection between the central terminal 19 and a selected terminal 12 is established by the use of a permanent magnet 25 which attracts the swingable plate 18 of the selected terminal 12 and thereby raises it to a position shown in broken lines in Figure 2; in this raised position the plate 18 engages the disc 20 and thus provides an electrical connection between the central terminal 19 and the selected terminal 12.

The magnet 25 fits into recesses 26 provided in the upper surface 27 of the cover 6 and situated directly above the compartments 11 and the swinging plates 18 which are located therein. The recesses 26 may be designated by suitable indicia 28 by means of which the various terminals 12 may be distinguished one from the other.

The magnet 25 is carried by a rod 29, the upper end of which is connected with a manually operated disc or button 30. The rod 29 extends through a sleeve 31 constituting a part of an arm 22. A coiled spring 33 encloses the rod 29 and is situated in a recess 34 provided in the sleeve 31. One end of the spring 33 engages the disc 30 while the other end presses against the bottom of

the recess 34. The lower surface of the arm 32 has a recess 35 into which the magnet fits and the spring 33 tends to move the magnet 25 into the recess 35 (Figure 3).

However, the rod 29 is locked in a downward position, in which the magnet 25 is situated in one of the recesses 26, by a locking member 36 which fits into a recess 37 provided in the rod 29. The locking member 36 is pressed against the rod 29 by a spring 38 situated in a passage 39 which is formed in the sleeve 31 and which is closed by a screw 40.

The arm 32 has an outer end 41 which may have the form of a pointer slidable over the surface 27 and adapted to be placed opposite any one of the indicia 28. The indicia 28 are so located that in these positions of the pointer 41, the recess 35 and the magnet 25 are located directly above a recess 26.

The inner end of the arm 32 has the form of a sleeve 42 which is mounted upon a pivot 43. The pivot 43 is firmly mounted in the cover 6 of the casing.

The switch is operated as follows:

Let it be assumed that an operator desires to use the switch for the purpose of providing an electrical connection between that terminal 12 which is designated by the numeral "4" in Figure 1, and the central terminal 19. Then the operator turns the arm 32 by holding the knob 30 until the pointer 41 of the arm is situated directly opposite the numeral "4." In this position the magnet 25 which is held in the recess 35 of the arm 32 by the spring 33, will be located directly above a recess 26.

Then the operator inserts the magnet 25 into that recess 26 by depressing the knob 30 and the arm 29 connected therewith. The recess 37 of the arm 29 will find itself opposite the passage 39 in the course of the downward movement of the arm 29, and then the locking member 36 will be pressed into the recess 37 by the spring 38. Thus the arm 29 will be locked in its depressed position in which the magnet 25 is located in the recess 26.

The plate 18 of the terminal 12 will be placed then in the magnetic field of the magnet 25, so that it will become magnetized and will swing from the position shown by full lines in Figure 2 to the position shown by broken lines therein. In the magnetized position the plate 18 is in engagement with the disc 20, so that an electrical connection is established between the wire 24, the terminal 19, the disc 20, the plate 18 and the terminal 12.

The partitions 8 and the location of the magnet 25 in a recess 26 are such that only one plate 18 situated directly below the magnet is influenced by it.

In order to disengage the switch, the operator pulls the knob 30 upwardly, causing the locking member 36 to recede into the passage 39. Then the magnet 25 is raised and moved into the recess 25 of the arm 32 by the spring 33. The arm 32 may be conveniently moved over the surface 27 of the cover 6, since the attractive force of the magnet is insufficient to actuate the plates 18 while the magnet 25 is located in its upper position in the recess 35 of the arm 32.

It is apparent that the switch shown above has been given by way of illustration and not by way of limitation and that it is capable of many variations and modifications without exceeding the scope or the extent of the present invention. All of such variations and modifications are to be included within the scope of the present invention.

What is claimed is:

In a switch, in combination, an insulating hollow casing, radially extending partitions situated within said casing and dividing the interior thereof into a plurality of segment-like compartments, terminals located within said compartments close to the outer walls thereof, comparatively wide plate-like magnetizable conducting members located within said compartments, said terminals comprising means pivotally supporting the outer ends of said plate-like members at a distance from the bottom of said compartments, whereby said plate-like members are downwardly inclined in the direction toward the common center of said compartments in the inoperative positions of said plate-like members, a central terminal carried by said casing substantially in the middle thereof and extending above the inner ends of said plate-like members, an insulating cover mounted upon said casing and having a plurality of radial recesses formed therein, said recesses being narrower than said plate-like members and being located directly above them, a permanent magnet fitting into said recesses, an arm mounted upon said cover and rotatable over said recesses, and means carried by said arm and carrying said magnet for moving said magnet into and out of any of said recesses, whereby said magnet may raise the inner end of any plate-like member located below it into engagement with said central terminal.
